Patented Oct. 4, 1910.

UNITED STATES PATENT OFFICE.

MARTIN STUCKEL, OF MACE, IDAHO.

DUST-CATCHER FOR DRILLS.

972,035.

Specification of Letters Patent.

Patented Oct. 4, 1910.

Application filed November 6, 1909. Serial No. 526,599.

To all whom it may concern:

Be it known that I, MARTIN STUCKEL, a citizen of the United States, residing at Mace, in the county of Shoshone and State 5 of Idaho, have invented new and useful Improvements in Dust-Catchers for Drills, of which the following is a specification.

My invention relates to certain new and useful improvements in dust catchers in 10 drilling and it consists in the novel combination and arrangement of parts as will be hereinafter more particularly described and pointed out in the claims.

In the drawings, Figure 1 is a side elevation of my complete invention as applied to the usual form of drilling machinery. Fig. 2 is a vertical longitudinal section of my complete invention taken on the line $x-x$ of Fig. 3. Fig. 3 is a horizontal cross section taken on the line $y-y$ of Fig. 2 about the base portion of my invention. Fig. 4 is a similar transverse section taken on the line $z-z$ of Fig. 2.

The object of my invention is to provide 25 a very practical and effective construction for dust catchers to be used particularly in connection with any suitably designed or manufactured mining drill and it consists primarily of a sack or inclosure for receiving 30 and confining the dust caused in drilling, said sack being constructed of suitable pliable or other textile material and being conical or funnel shaped and having its opposite upper and lower edges forming the ends 35 thereof, securely clamped to encircle the shaft and being turned by the latter, during the operation in drilling, and many other details in the construction and arrangement of the parts, as will more fully appear from 40 the detailed description to follow.

Referring to the drawings 1 represents a 45 pneumatic drilling machine of the usual construction, the air being supplied to the same by an ordinary hose or pipe 2, said machine also having the usual lever 3 for regulating the supply of air to the same or controlling the power to be applied thereto. The drill bar 4 which is operated in the usual manner by the machine previously referred to is polygonal in cross section, the lower end of said shaft carrying an ordinary drill or other tool 5 for drilling the ground, rock or other surface to be operated upon, the entire device so constructed and 55 arranged being held in its proper position and in the usual manner by a suitable beam

or other receiving surface 6, all of which are of the well known construction.

My invention therefore consists of a circular basal portion 7, preferably formed 60 from sheet metal and having an enlarged base 8 which is hollow, the terminal edge of the base thus formed having vertical parallel flat clamping surfaces or extensions 9, between which is located the lower circular 65 portion of the conical shaped sack 10 when the parts are properly clamped, thus securing the said sack firmly to the base thus formed, all of which is clearly shown in Fig. 2 of the drawing.

Encircling the upper inner portion of the base constructed as above described is an annular band 11, through which rivets, bolts or other similar devices may be passed into and through the vertical extensions 9 of the 70 base and also through the lower or that portion of the sack thus formed, thereby holding the several parts firmly together.

Encircling the bar 4 is a ring 12 somewhat larger than said bar and connecting said 75 ring to the band 11, are radially arranged arms 13, whereby said ring is firmly secured in its proper position in respect to the band, and also secured to the band 11 are the outer 80 ends of two yielding clamping arms 14, the 85 inner free ends of which are adapted to be brought into binding contact with the bar and having their ends so shaped as to correspond to the shape of the bar employed, so that a relative sliding movement of the parts 90 will be permitted, and at the same time the arms and base will rotate with the drill bar, all of which is clearly shown in Fig. 3 of the drawings.

Passing through the upper projecting portions 9 of the circular base 7 and also through that portion of the sack to be clamped and also through the band 11, are two set screws 15, the inner ends of which bear against the vertical portions 16 of the 100 arms 14, the said screws serving to hold the free ends of the arms 14 in engagement with the drill bar to prevent lateral movement of the base, but not sufficiently tight to prevent the arms sliding on the drill bar as the latter moves into the earth. Thus it will be seen that a circular base 8 which is in contact with the ground or other surface to be operated upon will rotate with the drill bar and at the same time the arms 14 will slide 105 on the drill bar to compensate for the inward movement of the said bar, so that all

dust or other accumulations caused in drilling will pass up through said base and is received and collected by the sack 10 into which the dust is finally confined. The upper end of the sack 10 also surrounds the drill bar 4 and is secured to the latter by means of two semi-circular clamping blocks 17, which when brought together form a central opening 18, which is approximately the same shape as the said bar, the blocks thus formed being constructed of hard rubber or other suitable pliable material.

The clamping blocks 18 are provided with lower semi-circular extensions 19 which likewise embrace the bar 4 and covering the blocks thus formed together with the extensions is a metallic casing 20 made of two semi-circular sections hinged at 21 and provided with a suitable fastening device 22 at their opposite edges, whereby the clamping blocks 18 are properly held and confined within the casing thus formed. Fixed to the inside of the metallic casing 20 thus formed are the ends of two yielding springs 23 which are adapted to be brought into contact with the binding blocks 18 for holding the latter in a rigid position in respect to the bar 4 and protecting the material of which the said blocks are composed, binding screws 24 being employed and brought in contact with the said springs, as clearly shown in Fig. 4 of the drawing. The lower portions of the semi-circular sections of the metallic casing 20 are U-shaped as shown at 25 and are adapted to securely receive the upper circular edge or end of the bag or sack 10, as clearly shown in Fig. 2 of the drawing, rivets or bolts 26 being passed through the several connecting parts for securing the same together.

During the operation of the device the base may be manually elevated a distance from the ground or other surface operated upon to a sufficient height to permit the dust to be removed from under the base, the flexibility of the sack thus employed permitting this operation and manipulation of the several parts.

Having thus fully described the invention what is claimed as new is:

1. In a dust catcher for drills, a flexible sack encircling the drill bar, a lower an-

nular base for said sack adapted to bear upon the ground, means for fixedly securing the upper portion of the sack to the drill bar, and a clamp engaging the drill and carried by the base and adapted to turn with and slide on the drill bar.

2. A dust catcher for drills comprising a lower annular base, yielding arms extending rigidly from the inner periphery of the base, the free ends of said arms bearing on the drill bar and adapted to turn with and slide on the drill bar, set screws carried by the base for holding the arms in engagement with the bar, a clamp fixedly secured to the drill bar above the base, and a flexible sack having its opposite ends secured to the clamp and base.

3. A dust catcher for drills comprising an annular base to surround the drill bar, means for loosely securing said base to the drill bar, an upper clamp including a pair of semi-annular blocks adapted to be secured to the drill bar, a metallic casing surrounding the blocks and including two semi-circular sections, curved spring arms interposed between the casing and blocks, means for holding said arms in binding contact with the blocks, and a flexible sack having one end secured to the base and its opposite end fixed to the said clamp.

4. A dust catcher for drills comprising an annular base, a band secured on the inside of the base, a central ring encircling the drill bar, radially arranged arms connecting said ring to the band, yielding arms attached to the band and having their inner ends shaped to correspond substantially to the shape of the drill shaft, set screws passing through the base and bearing against the said arms, a clamp surrounding the drill bar at a point above the base, means for fixedly securing the clamp to the drill bar, and a conical-shaped flexible sack encircling the drill bar and having its opposite ends secured to the clamp and base.

In testimony whereof I affix my signature in presence of two witnesses.

MARTIN STUCKEL.
